C. W. COLEMAN INVENTOR

BY
Emil F. Lange ATTORNEY.

UNITED STATES PATENT OFFICE.

CLYDE W. COLEMAN, OF LINCOLN, NEBRASKA.

OIL-STRAINER HEATER.

Application filed February 19, 1924. Serial No. 693,944.

To all whom it may concern:

Be it known that I, CLYDE W. COLEMAN, a citizen of the United States, residing at Lincoln, in the county of Lancaster and State of Nebraska, have invented certain new and useful Improvements in Oil-Strainer Heaters, of which the following is a specification.

My invention relates to a device for utilizing the heat of a portion of the exhaust gases of an internal combustion engine for the purpose of directly heating the oil strainer in the crank case of the engine.

It is a well known fact that in very cold weather the oil in the crank case of an internal combustion engine becomes thick, so that after starting the engine it is difficult to establish a flow of the oil through the pump and through the strainer. The oil usually contains water in suspension, and this water at freezing temperatures tends to separate from the oil and to congeal, the ice being generally formed on the strainer. When the strainer is thus covered with ice, the pump cannot circulate the oil and the engine suffers the usual disastrous results caused by improper, insufficient, or no lubrication. In brief, it is the object of my invention to provide a device whereby these troubles will be avoided and prevented.

More specifically, my invention has for its objects the provision of a device which can be produced at a low cost, which can be easily installed on an internal combustion engine of any type, which utilizes the exhaust gases and thus entails no cost of operation, which directly heats the strainer, and which produces the desired results almost instantly.

Having in view these objects and others which will be pointed out in the description, I will now refer to the drawings, in which—

Figure 1 is a view in perspective of the oil strainer with the heating coil secured thereto.

Figure 2 is a view in perspective of a portion of an internal combustion engine with my heater attached thereto.

The engine which I show in Figure 2 is the conventional automobile engine, but from the following description it will be apparent that the heater may be applied to gas engines of any or all types.

Numeral 10 designates the plate which in some types of engines carries the strainer. The plate 10 has apertures 11 whereby it

may be secured to cover the opening in the crank case of the engine. Centrally positioned in the plate 10 is an aperture in which is secured the return oil pipe 12 whereby the circulation of the oil through the strainer is maintained.

In carrying out my invention as it pertains to engines having a plate similar to that shown at 10, I provide the plate with two additional apertures through which the coil 13—14 is passed, 13 being the inlet end and 14 the outlet end. A channeled strip 15 of suitable sheet metal surrounds the outer surface of the coil, the ends of the strip being secured to the plate 10 on its inner side. Two strips 16 of metallic gauze or other suitable straining material are secured at their edges to the channeled strip 15 in such a manner as to cover on both sides the spaces between the arms 13 and 14 of the coil.

The structure as above described is a combined strainer and heater. In applying it to the engine, for example of a Dodge car, I remove the strainer which is on the engine and insert my combined strainer and heater. The securing means which I have shown in my drawings are similar to those of the engine on the Dodge car but it is evident that these means may be modified and altered in such a manner that the device may be secured to the engines of the cars of any other make, or in fact to any other internal combustion engines, whether portable or stationary.

After the plate 10 has been secured to the crank case, the oil pipe 12 is connected to the crank case by means of the tube 12' in such a manner that circulation of the oil through the strainer can be established. I then provide a small aperture in the exhaust at the most desirable and convenient point and I then insert a shut off valve in the aperture. This valve I connect with the pipe 13 by means of the tube 16 which completes the installation.

In cold weather the valve is first opened and the engine is then started. The main portion of the exhaust gases will of course pass out through the usual channel but a portion of the exhaust gases will travel through the by-pass 16 and thence through the coil and out through the opening in the pipe 14. The heat of this latter portion of exhaust gas is absorbed by the oil immediately surrounding the strainer. The heat

thus absorbed is almost instantaneous in action in thinning stiff oil or in thawing ice which encases the strainer and which thus stops the circulation of the oil through the 5 strainer. By actual tests it has been found that a thawing temperature on the strainer can be obtained in from five to ten seconds with the use of my device and that normal circulation of the oil can be established in 10 less than thirty seconds after starting the engine. After the oil has been warmed sufficiently the valve may be closed as the circulation of the oil in the crank case will keep the strainer clear. Likewise during 15 warm weather the valve should be kept closed to avoid the undue thinning of the oil. My device may be used advantageously during the changeable weather in the late autumn before the lighter winter oils are 20 used. It frequently happens that autumn days are very frosty and cold in the early morning but hot in midday, thus making it difficult to choose the proper oil for that season. The stiff summer oil may be of the 25 right consistency at noon but too stiff in the morning to pass through the strainer. With my device it is only necessary to open the valve for a few minutes while the engine is running, the oil being thus brought to the 30 proper consistency in a very short time.

In constructing the combined strainer and coil, I prefer to turn the inner end upwardly as shown in Figure 1, so that the inner extremity will be at or near the level of the 35 upper surface of the oil in the crank case. In my preferred construction I use copper tubing for the coil 13-14 and for the oil outlet 12 as well as for the tubes 12' and 16, and I cast the plate 10 of bronze or brass. 40 I have shown the strainer strips in the form of perforated sheet metal, but it is obvious that in the choice of materials numerous others could be found which would serve the purpose equally well and for that reason I 45 do not desire to restrict my rights to any specific material or materials. It is also my desire to adapt my combined heater and strainer to any and all types of internal combustion engines and to make such changes 50 in the disclosed construction as are necessary for such adaptations. I therefore reserve to myself the right to any or all equivalents of the structure which I show and claim, and to any and all portions 55 thereof.

Having thus described my invention in terms which will be readily understood by others skilled in the art to which it pertains, what I believe to be new and desire 60 to secure by Letters Patent of the United States is:—

1. A combined heater and oil strainer which is adapted to be used on the crank case of an internal combustion engine, said 65 combined heater and oil strainer comprising

an elongated strainer, a tubular coil within said strainer, said coil being provided with intake and outlet ends positioned outside said strainer, and a tubular by-pass which is adapted to be connected with the exhaust 70 of the engine and with the intake end of the said coil.

2. A combined heater and oil strainer which is adapted to be secured to the crank case of an internal combustion engine 75 through an opening thereof, said combined heater and oil strainer including a plate for closing the opening in the crank case, a strainer secured to said plate on the inner side thereof, a tubular coil within said 80 strainer, said tubular coil passing into and out of said plate and having its intake and outlet ends positioned on the outer side of the plate, and a tubular by-pass secured to said coil at its intake end, said tubular by-pass being adapted to be connected at its other end with the exhaust of the engine. 85

3. A combined oil strainer and heater which is adapted for use inside the crank case of an internal combustion engine, said combined oil strainer and heater comprising 90 a plate which is adapted to cover the opening in the crank case, said plate having means for securing it in position on the crank case, a strainer secured to the plate 95 at the inner side thereof, a tube passing through said plate into said strainer, said tube being adapted to be connected at its outer end with the crank case whereby circulation of the oil may be maintained 100 through said strainer, a tubular coil within said strainer and having its ends projecting through the said plate, and means for connecting one of said ends to the exhaust of the engine, said means serving to deflect a portion of the exhaust gases through the 105 coil and to thus heat the strainer, the other of the ends of the coil being the discharge end for the exhaust gases thus deflected.

4. A combined oil strainer and heater 110 comprising a tubular coil having a pair of substantially parallel portions, the inner end of said coil being upwardly and inwardly inclined, a plate which is adapted to close the opening in the crank case of an internal 115 combustion engine, said plate being provided with a pair of apertures for receiving the ends of said coil with the ends of the coil projecting outside the said plate, a sheath of channeled metal surrounding the 120 outer edges of said coil, a pair of strainers secured to said sheath on opposite sides of the coil, means for connecting one of the projecting ends of the coil with the exhaust 125 of the engine, and means for permitting a circulation of the crank case oil through said strainer.

In testimony whereof I affix my signature.

CLYDE W. COLEMAN.
